C. S. VALE

DISINFECTING CABINET AND THE LIKE

Filed Nov. 30, 1926

Inventor,
C. S. VALE.

Per R. H. Blair Atty.

UNITED STATES PATENT OFFICE.

CHARLES SILLERY VALE, OF BIARRITZ, FRANCE.

DISINFECTING CABINET AND THE LIKE.

Application filed November 30, 1926, Serial No. 151,715, and in Great Britain December 15, 1925.

This invention relates to disinfecting cabinets for clothing, household linen and the like and has for its object not only to provide an article of domestic furniture which 5 can be readily used without risk of fire, but further to provide means whereby the unpleasant after effects of disinfectant gas can be obviated.

As hitherto no satisfactory domestic disinfecting apparatus has existed, it has been necessary to send articles of clothing, household linen, blankets or the like to some establishment which specializes in such treatment or to seal up an entire room and 15 fumigate the articles by burning some disinfectant in the room. In the former case the articles are often exposed to infection for example in transit, before being returned to their owners and the expedient of fumigation by sealing up a room is both inconvenient and of doubtful efficiency. Owing to the lack of some ready means for disinfecting such articles of clothing or the like which are frequently exposed to infection, 20 often without their owner's knowledge, they are seldom if ever disinfected as often as they should be, and in this way many infectious diseases are generally spread.

According to this invention a cabinet or 30 wardrobe is provided which does not differ in general external appearance or dimensions from an ordinary piece of household furniture and comprises a main compartment to receive the garments or other articles to be disinfected which can be hermetically closed and within which a disinfectant gas can be liberated without the employment of fire, and a secondary compartment containing means whereby the disinfectant gas 35 can subsequently not only be driven out of the main compartment through suitable valve-controlled passages but further replaced by a neutralizing gas before the closing door is again opened. The second compartment may be formed to one side of or 40 below the main compartment, and the fan or bellows which it contains is so arranged that the air which it draws or forces through the main compartment is made to pass 45 through some substance which causes it to neutralize the disinfecting gases as well as expelling them through the outlet opening. The outlet opening in the main chamber is 50 preferably formed in the upper wall or roof thereof and may communicate directly with the atmosphere, for example, through a win-

dow or through the chimney of the room, or in some cases a flexible pipe may be provided by means of which the interior of the disinfecting chamber may be placed in communication with the atmosphere after the outlet valve has been opened, the flexible pipe being conveniently coiled up and stored on the top of the cabinet when it is not in use. 60

Obviously the nature of the device for forcing air and neutralizing gases through the main chamber may be considerably varied to suit the general dimensions and character of the cabinet or wardrobe, in all cases however the arrangement being such that after the contents of the main cabinet have been exposed for the necessary period to the action of the disinfecting gases, the latter can be readily and quickly expelled 70 by means of a device which forms an integral part of the article of furniture. 75

The disinfectant employed may vary so long as the gases are liberated without the use of fire inside the main compartment itself or in a compartment adjacent thereto and communicating therewith and forming an integral portion of the cabinet or wardrobe, since in all cases the invention comprises a self-contained unit having its own disinfecting chamber and means both for liberating and for expelling and neutralizing the disinfecting gases. 80

One construction of wardrobe or cabinet according to this invention is illustrated in 90 a diagrammatic manner in the accompanying drawings, in which:—

Figure 1 is a front elevation showing the door closed, and

Figure 2 is a sectional side elevation. 95

In the construction illustrated, the wardrobe comprises a main compartment A provided with a door B by means of which the main compartment can be hermetically closed. Below the main compartment is a 100 second compartment or chamber C which communicates with the main compartment by means of an inlet valve C¹, which may be of the non-return type indicated or furnished with some positive operating means such as a slide or shutter. The valve C¹ in the construction diagrammatically shown can open in an upward direction but prevents any gases passing downwards from the main chamber A into the second chamber C. In the upper wall or roof of the main chamber A is an outlet opening D 105

which can be closed by means of a slide or shutter D¹ without it being necessary to open the door B. The outlet opening D may be provided with a flexible or other pipe D² which may be coiled up so as to be concealed by means of the cornice A¹ when not in use, or taken to any suitable outlet in the room, for example, to the window or chimney. At its outer end (not shown) the flexible or other pipe D² may be provided with a positive control cock instead of or in addition to the slide D¹.

The second compartment C contains a device for forcing air drawn from the atmosphere through the main chamber A. To this end a series of air inlet openings E are formed in the walls of the compartment and mechanism is provided within the compartment for forcing air drawn in through these openings through the inlet port C¹ in the base or floor of the main compartment. In the construction diagrammatically illustrated, the air forcing device comprises a bellows arrangement F provided with an operating lever F¹ pivotally mounted at F² and connected through a slot in the side wall of the cabinet with a stirrup-shaped member F³ which bridges the bellows. The air is admitted into the bellows F by means of a flap valve F⁴ in the base of the bellows but instead of the atmospheric air passing directly into the bellows, it is caused to flow through some such substance as carbonate of ammonia arranged in a drawer or tray G below the bellows so that the air drawn in through the openings E must necessarily pass through this material before being admitted to the bellows through the inlet valve F⁴ and discharge into the disinfecting chamber through the valve C¹. As the drawer G is readily removable, the material which it contains can be replaced from time to time without difficulty.

When the apparatus is to be used for disinfecting purposes, the door is opened and the articles to be treated are suspended or otherwise arranged inside the main compartment A any known system of shelves, hooks or hangers which are in themselves known, and therefore are not illustrated, being used for this purpose.

Upon the base or floor of the main compartment is then placed a disinfecting carton containing a suitable disinfectant and a substance which will cause the disinfectant to be vapourized without the employment of fire when water is added thereto. The dimensions of the carton and the nature of its contents may of course be varied without departing from the present invention and the carton illustrated at H in Figure 2 of the drawings is shown merely by way of example in a diagrammatic manner, itself forming no part of the present invention.

As soon as water has been added to the carton, the door B is closed, care being taken to see that the outlet valve D¹ or its equivalent at the free end of the flexible outlet pipe D² has previously been closed. The valve C¹ by means of which air or neutralizing gas is admitted to the main compartment is automatically closed but, if desired, may be provided with some closing device of any known type. 75

After the articles to be disinfected have been subjected to the action of the disinfectant gases for a sufficient period, the free end of the flexible pipe D² is placed in the chimney or through an open window; if it does not already communicate therewith, the outlet valve D¹ or its equivalent at the free end of the tube is opened and the operating handle F¹ of the bellows is actuated. In this way atmospheric air from the room is drawn in through the openings E and caused to flow through the material contained in the drawer or tray G into the bellows F through the inlet valve F⁴ being then forced by means of the bellows through the inlet valve C¹ into the main chamber A so that the disinfecting gases which the main chamber contains are expelled through the outlet D and pipe D² and are further replaced by a neutralizing gas, since in passing through the tray G, the air drawn in through the openings E has taken up the carbonate of ammonia or other material contained therein. 85

The relative dimensions of the main compartment and the bellows can be so arranged that the entire gaseous contents of the main compartment can be expelled into the atmosphere either through the window or up the chimney after the actuating lever F¹ has been operated a few times, so that when the main door B is opened, not only will all the gases liberated by the disinfectant carton be completely expelled, but in addition, any trace of these gases which might be retained by the articles being disinfected will have been neutralized. 100

It will be appreciated that the construction is capable of considerable variation without departing from this invention and that although the bellows are shown below the floor of the main chamber, they may be disposed in a compartment on either side thereof or in any other convenient position. Further, if desired, the carton can be housed in a recess formed in the floor or base of the main chamber instead of resting on the base as shown. It will further be appreciated that although primarily designed for use for disinfecting purposes, a wardrobe or cabinet according to this invention can at other times be treated for the storage of clothes or linen in the ordinary way and since, in external appearance, it does not differ from an ordinary piece of 110 115 120 125 130

furniture, it is possible to convert existing wardrobes into disinfecting cabinets according to this invention, or to replace existing wardrobes with a disinfecting cabinet as above described without diminishing the accommodation available for the storage of clothing or other articles.

What I claim as my invention and desire to secure by Letters Patent is:—

- 10 1. A disinfecting cabinet comprising in combination a main compartment having a gas outlet therein, a valve controlling said outlet, a door by means of which said compartment can be hermetically sealed, a second compartment having an air inlet port and an outlet opening communicating with the main compartment, a valve controlling said outlet, means for generating a disinfectant gas within the main compartment
- 15 20 without the employment of fire, a receptacle containing a neutralizing substance within the secondary compartment, and means for drawing air into the second compartment and forcing it into the main compartment after it has passed over the neutralizing substance to discharge and replace the disinfectant gas which escapes through the gas outlet in the main compartment prior to the opening of the main compartment door as set forth.
- 25 30 2. A disinfecting cabinet comprising in combination a main compartment having a gas outlet therein, a valve controlling said outlet, a door by means of which said compartment can be hermetically sealed, a second compartment having an air inlet port and an outlet opening communicating with the main compartment, a valve controlling said outlet, a receptacle within the main

compartment containing a disinfectant and a substance which will vapourize the disinfectant when liquid is added thereto, a receptacle containing a neutralizing substance within the second compartment, and means for drawing air into the second compartment and forcing it into the main compartment after it has passed over the neutralizing substance to discharge and replace the disinfectant gas which escapes through the gas outlet in the main compartment prior to the opening of the main compartment door as set forth.

3. A disinfecting cabinet comprising in combination a main compartment having a gas outlet therein, a flexible conduit connected to said outlet, a valve controlling said outlet, a door by means of which said compartment can be hermetically sealed, a second compartment having an air inlet port and an outlet opening communicating with the main compartment, a valve controlling said outlet, a receptacle within the main compartment containing a disinfectant and a substance which will vapourize the disinfectant when liquid is added thereto, a receptacle containing a neutralizing substance within the second compartment, and means for drawing air into the second compartment and forcing it into the main compartment after it has passed over the neutralizing substance to discharge and replace the disinfectant gas which escapes through the gas outlet in the main compartment prior to the opening of the main compartment door as set forth.

In testimony whereof I have signed my name to this specification.

CHARLES SILLERY VALE.
